UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

FURRING STAPLE.

Application filed March 11, 1926. Serial No. 93,940.

My invention relates to furring staples adapted to be used in conjunction with wire lath in stucco construction, although also useful for other purposes, and one of the 5 objects thereof is the provision of a furring staple of comparatively broad span having its ends formed into fastening prongs adapted to be driven through the building paper into the wall sheathing of a stucco 10 structure, for attaching the staple thereto, the said prongs provided with sealing blocks adapted to seat against said building paper, said sealing blocks adapted, (1), for preventing water that may leak through the 15 stucco composition from the exterior, to said building paper, from passing to the punctures in the latter made by driving the prongs therethrough, and passing through said punctures to the wood-work of the structure, by maintaining a water tight connection 20 between said building paper and sealing blocks, (2), for providing cushioning means between the building paper and the body of the staple adjacent the prongs, for preventing 25 injury to said paper by engaging it with said body in case the prongs are accidentally driven excessively in attaching the staple to the wall sheathing, (3), for spacing the body of the staple a suitable distance from the 30 face of the building paper.

With the foregoing and further objects and purposes in view which will appear as the description proceeds, my invention resides in the combination and arrangement of 35 parts and in the details of construction hereinafter described and claimed, it being understood that changes in the precise embodiment of the invention herein disclosed can be made within the scope of what is claimed 40 without departing from the spirit of the invention.

In the accompanying drawings—

Figure 1 is a face view of a portion of the 45 wall sheathing, building paper and wire lath of a stucco structure, and one of the present furring staples applied thereto;

Figure 2 is a side elevation of one of the staples attached to the wall sheathing;

Figure 3 is a view similar to Fig. 2, but 50 with portions of the staple and the wall

sheathing and building paper shown in section;

Figure 4 is a perspective view of the staple detached from the wall sheathing;

Figure 5 is a view on line 5'-5' of Fig. 2; 55

Figure 6 is a plan view of one of the sealing blocks detached from the staple;

Figure 7 is a transverse sectional view of the staple, showing the body of the staple partly embedded in the upper surface of one 60 of the sealing blocks; and

Figure 8 is a view similar to Fig. 7, but showing the body portion disposed across the upper surface of the sealing block but not embedded therein. 65

Referring to the drawings in detail, throughout which like reference characters designate like parts:

The numeral 1 designates the usual wall sheathing or sub-siding secured to the wall 70 timbers of a stucco structure. Across the face of the wall sheathing 1 is disposed a covering of building paper 2 to prevent moisture in the stucco composition leaking therethrough from the exterior, penetrating to the 75 wall sheathing and other wood-work of the structure.

3 designates the present furring staple, which comprises a body 4, preferably formed of round wire, has a centrally disposed offset 5, and has its ends struck to one side to form a pair of spaced fastening prongs 6, the latter provided with sealing blocks 7, which are preferably formed of fibrous material impregnated with water resisting 80 binding material, and are provided with perforations 8, preferably centrally disposed, through which the prongs project and in which they are intended to be sufficiently tightly wedged to resist removal therefrom. If preferred, the perforations 8 may be omitted and the prongs forcibly projected directly through the body of the blocks. 85

The sealing blocks 7 are intended to be carried on the prongs, preferably adjacent the body portion 4, as best shown in Figs. 2, 3 and 8, and form portions of the present 90 furring staples.

The staples are adapted to form projec- 100

tions on the face of the building paper 2, for maintaining the wire lath 9 in spaced relation thereto, thereby providing proper key space therebetween for the stucco composition (not shown), as well as providing outstanding supports on and around which the stucco composition is spread for binding it permanently to the wall.

The sealing blocks 7 are adapted to form cushioning means between the building paper and the body 4 of the staple, for absorbing any accidental excessive driving of the prongs when attaching the staple to the wall sheathing and thereby preventing injury to the building paper which the unprotected body portion 4 might cause when forced thereagainst. The sealing blocks 7 are further adapted to form means bearing against the building paper to maintain a water tight connection therebetween, whereby water leaking through the stucco composition from the exterior is prevented from penetrating to the punctures made in the building paper by the passing therethrough of the fastening prongs 6, and from said punctures penetrating to the wood-work of the wall.

The off-set 5 is adapted to form a support for the intermediate portion of the body 4 and to coact with the sealing blocks for maintaining the body in spaced relation to the wall sheathing 1 and building paper 2.

To apply my improved furring staple, the prongs 6 are driven forward into the wall sheathing through the building paper, until the body portion 4 binds the sealing blocks 7 firmly against said building paper and the latter against the wall sheathing. After attaching a suitable number of the staples to the wall sheathing, the wire lath 9 is secured by disposing it across the staples and driving suitable nails 10 part way in the wall sheathing through the lath and then bending them over against the latter. Obviously, other fastening elements may be employed for attaching the lath to the wall sheathing.

The furring staples may be disposed along on the wall sheathing at such intervals as may be found best suited for the work to be performed. I have found by practice that spacing them about 9 inches apart provides ample fastening for securing the building paper, as well as ample furring for the general types of wire lath commonly used for stucco reinforcement, including the wire lath known as "poultry netting".

I claim:

1. A furring staple having a pair of spaced fastening prongs provided with sealing blocks formed of fibrous material relatively softer than said staple.

2. A furring staple of the character described, comprising, a body portion having its ends formed into spaced fastening prongs

and having an intermediate portion off-set in the plane of said prongs, said prongs penetrating sealing blocks formed principally of fibrous material relatively softer than said staple, whereby portions of the latter will become partly embedded in the upper surfaces of said blocks when said staple is secured to a support by driving said prongs therein a proper distance.

3. In combination, building paper, a furring staple, sealing blocks interposed between the ends of said staple and said building paper, and fastening means on said ends projecting through said sealing blocks and through said building paper, said means adapted to be driven in a support for binding said sealing blocks and building paper together, said sealing blocks formed of composition material relatively softer than said staple.

4. In combination, building paper, a furring staple, a sealing block formed of fibrous material disposed between each end of the latter and said building paper, and fastening prongs on said ends projecting through said sealing blocks and through said building paper, said prongs adapted to be projected in a support, said support and building paper and sealing blocks and fastening prongs cooperable for forming a water tight connection between said sealing blocks and building paper.

5. In means of the character described, a strip of wire, a prong at each end thereof, a pair of sealing blocks formed of composition material relatively softer than said wire through which said prongs project, said sealing blocks adapted to seat against a support into which said prongs are adapted to be driven, said strip of wire having an off-set intermediate said prongs, said off-set adapted to seat against said support.

6. In means of the character described, a pair of sealing blocks constructed principally of fibrous material, and a strip of wire having its ends formed into a pair of spaced prongs projecting through said sealing blocks, portions of said wire adjacent said prongs being partly embedded in the surfaces of said blocks.

7. In means of the character described, a pair of sealing blocks of comparatively soft material, a strip of wire of relatively hard material, said wire having its ends formed into fastening prongs penetrating said sealing blocks, said sealing blocks and said prongs coacting to resist separation.

8. In means of the character described, a pair of sealing blocks of comparatively soft material, and a strip of wire of relatively hard material, said wire having its ends formed into fastening prongs extending through said sealing blocks, said sealing blocks adapted to seat against building paper secured to the wall sheathing of a

structure, said prongs adapted to be projected through said building paper and in said wall sheathing for cooperating therewith for binding said building paper and sealing blocks together, said wire having an off-set intermediate said prongs, said off-set and said sealing blocks adapted to coact

for maintaining the body portion of the wire in spaced relation to said building paper and wall sheathing. 10

In testimony of the foregoing being my own, I have hereunto affixed my signature this 4th day of March, 1926.

GEORGE F. VOIGHT.
